UNITED STATES PATENT OFFICE

2,587,952

GRINDING MACHINE

Amedee D. Appleby, Odessa, Tex.

Application December 27, 1946, Serial No. 718,738

8 Claims. (Cl. 51—105)

1

This invention relates to improvements in grinding machines of the character adapted particularly for the grinding of ball or roller bearing races on odd or irregularly shaped devices, such as the segments of rock bits used on rotary well drills in the drilling of deep wells.

While various machines have been proposed heretofore for grinding the cups and cones of rotary bits and the like, these for the most part have lacked the flexibility for performing the desired grinding action and have not been constructed so as to be capable of grinding both the convex and concave races in cones and cups, as is often desired.

One object of this invention is to improve the construction of grinding machines, so that a machine may be capable of grinding both the cups and cones of a rock bit or other parts of an irregular piece of machinery without requiring separate machines or devices for the respective convex and concave objects.

Another object of the invention is to provide a grinder that may be adjusted readily with respect to the work and on which the work may be secured in place with facility for the performance thereon of the necessary grinding operation.

Still another object of the invention is to improve the construction of the grinding machine to perform the desired grinding operation by means of a machine which is simple in construction, light in weight, and which may be moved readily from place to place, as desired.

In carrying out these objects, a grinding machine may be so constructed as to provide for mounting of the object thereon and securing it in proper relation to the grinding element. Provision is made to adjust the position of the support and the grinding element relative to each other so these may be brought into the proper relation, both axially and angularly, for the proper alignment and positioning of the respective parts of the machine and to provide for the correct operative relationship between these parts. Both the grinding element and the mounting for the work may be power driven in operative relation to accomplish the desired grinding action. By the adjustments provided, the machine can be used for grinding the cups and cones of both convex and concave races, or other irregularly shaped objects, as desired.

Certain embodiments of the invention are illustrated in the accompanying drawings, in which:

Fig. 1 is a perspective view of one form of grinding machine embodying this invention;

2

Fig. 2 is a side elevation of the operating structure thereof;

Fig. 3 is a vertical sectional view through the grinding portion of the machine, substantially on the line 3—3 of Fig. 2;

Fig. 4 is a horizontal sectional view through the machine showing the work holder in plan, substantially on the line 4—4 of Fig. 2;

Fig. 5 is a horizontal section substantially on the line 5—5 of Fig. 2, and showing the driving connections for the operating parts;

Fig. 6 is a vertical section through the jack shaft mounting on the line 6—6 of Fig. 2;

Fig. 7 is a detail horizontal section through the spindle mounting clamp on the line 7—7 of Fig. 2;

Fig. 8 is a longitudinal sectional view through the work-holder on the line 8—8 of Fig. 4;

Fig. 9 is a transverse sectional view therethrough on the line 9—9 of Fig. 2;

Fig. 10 is a perspective side view of a modified form of the invention;

Fig. 11 is a view similar to Fig. 10, but from the opposite side thereof; and

Fig. 12 is a perspective view of the rotary table as shown in this modified form.

Referring to Figs. 1 and 2 of the drawings, the operating mechanism of the machine is shown as mounted on a supporting stand which may be seated on the floor, although any other suitable form of mounting may be used, as desired. This stand is formed by a base 1, upon which is supported an upright standard 2. Carried by the upper end of the standard 2 is a supporting member 3, shown as in the form of a plate which is provided with a sleeve 4 fitted over the standard 2, and the plate extends transversely to opposite sides of the standard and supports thereon the operating mechanism of the machine.

Referring to Figs. 1, 2 and 6, the support 3 has upstanding therefrom a bushing 5, fixed to the support and internally threaded for screw-threaded connection with the threaded lower portion 6 of an upstanding sleeve 7. These parts may be locked together by a handwheel 8, which is screw-threaded on the portion 6 of the sleeve into abutting relation with the upper end of the bushing 5. This forms a support for the sleeve 7 and holds it rigidly in place for mounting the grinding spindle as hereinafter described.

Telescoped over the upper end portion of the sleeve 7 are spaced bushings 9 and 10 which are also journaled on the sleeve 7 and are capable of vertical adjustment relative thereto. The bushings 9 and 10 are supported in their elevated positions by the skirt portion 11 of a handwheel

12 which is screwed onto the threaded portion 6 of the bushing 7. By adjusting the handwheel 12, the bushings 9 and 10 may be adjusted vertically relative to the sleeve 7.

The bushings 9 and 10 are held in spaced relation by a clamping segment 13 which fits between the bushings 9 and 10 in embracing relation with the sleeve 7, as shown in Figs. 6 and 7. The clamping segment 13 is attached through a journal connection to the inner end of a threaded stem 14 which is screw-threaded through a bushing 15, and is provided with a crank 16 on the outer end thereof, as a suitable means for rotating the threaded stem 14, as shown clearly in Fig. 7. The threaded bushing 15 is mounted on a bracket 17 which extends in bridging relation between the adjacent ends of the bushings 9 and 10, as shown in Figs. 1 and 2. The threaded stem 14 may be adjusted to press the clamping segment 13 into frictional engagement with the periphery of the sleeve 7 for securing the bushings 9 and 10 in adjusted positions vertically along the axis of the sleeve.

Extending horizontally from the bushings 9 and 10 are support arms 18 and 19, respectively, rigidly attached to the bushings at one end, as by welding, and at the opposite end being similarly attached to an upright sleeve 20 having an axis extending parallel with the axis of the sleeve 7 and carried thereby for swinging movement to different positions relative thereto.

As shown in Fig. 3, the sleeve 20 supports a grinding spindle 21, journaled therein by anti-friction bearings 22 and 23 which are confined in the sleeve by adjustment nuts 24 and 25, having screw-threaded connection with opposite end portions of the sleeve.

The lower end of the grinding spindle 21 is shown as provided with a grinding element 26, such as an emery wheel, although any suitable form of abrasive device may be provided thereon as desired.

The upper end of the grinding spindle 21 has a pulley 27 fixed thereon. The pulley 27 is shown in Figs. 1 and 2, as connected by a belt 28 with a pulley 29, fixed to the upper end of a jack shaft 30 (Fig. 6).

The jack shaft 30 extends vertically through the sleeve 7 and is journaled in anti-friction bearings 31 and 32 therein. The bearings 31 and 32 may be adjusted and are confined by adjustment nuts 33 and 34, which are threaded into opposite ends of the sleeve 7 in the form illustrated.

The lower end of the jack shaft 30 is provided with a pulley 35 fixed thereon. The pulley 35 is connected through a driving belt 36 with a pulley 37 mounted on the armature shaft of an electric motor 38, in the form illustrated in Figs. 1 and 2, which forms the source of power for driving the operative parts of the machine. The electric motor 38 is shown as mounted on brackets 39, secured to one end of the support 3.

The spindle 21 is capable of axial adjustment relative to the support sleeve 7, as well as circumferential adjustment relative thereto. To provide for these adjustments, I have shown an arm 40, extending radially from the bushing 9 in the opposite direction from the supporting arm 18. The outer end of the arm 40 carries a crank rod 41, journaled therein on a swivel, the threaded portion of which rod is shown as engaging an internally threaded bushing 42,

mounted between upstanding posts 43 shown as slightly spaced apart and carried by the support 3. This will provide adjustment of the arm 40 about the axis of the sleeve 7, thereby circumferentially adjusting the grinding spindle 21 therearound. It will permit also axial adjustment of the spindle 21 relative to the sleeve 7, while maintaining the same angular position relative thereto, which is permitted by the swiveled connection of the crank rod 41 with the arm 40.

Referring to Fig. 3, the opposite end of the support 3 is shown as formed with a depending bushing 44. A shaft 45 extends upwardly through the bushing 44 and is journaled in anti-friction bearings 46 and 47, adjacent its opposite ends.

Mounted on the upper end of the shaft 45 is a turntable 48, which is not only keyed to the shaft at 49, but is also secured rigidly thereto at 50. The turntable 48 forms the work support and has provision thereon for supporting the work in an operative relation with the grinding element 26.

In the form of the invention illustrated in Figs. 3, 8 and 9, in which the work to be ground may comprise elements of a rock bit, generally indicated at B in Fig. 8, such as a raceway R on a bit segment, provision is made for mounting this segment on the turntable 48 for adjustment to different angular positions with respect to the grinding element 26.

In this form, an adjustable support is provided at 51 having an eye portion 52 along one edge thereof, the support 51 being shown as preferably in the form of a plate. The eye portion 52 is sleeved over a rod 53 with which it has screw-threaded adjustment at 54, for adjustment of the support 51 longitudinally of the rod 53 upon rotation of said rod. The rod 53 is journaled in brackets 55 and 56, upstanding from the turntable 48, and is provided with a hand crank 57, as a suitable means for adjustment of the rod to accomplish the desired adjustment of the support 50. The support 51 is also capable of being tilted to different angular positions by means of adjusting screws 58, which are threaded through ears 59 formed on opposite edges of the support 51 and bear upon the upper face of the turntable 48, as will be evident from Figs. 8 and 9.

A second support is shown at 60 as mounted upon the support 51. The support 60 has a sleeved portion 61 journaled on a rod 62 with which it also has screw-threaded connection for adjustment of the support 60 along the support 51 upon rotation of the rod 62. The rod 62 is shown as provided with a hand crank 63 for turning movement thereof. This rod is journaled in upstanding brackets 64 mounted on the support 51. The support 60 is capable of transverse adjustment by an adjusting screw 65 threaded through an ear 66 formed on the support 60 and into engagement with the upper face of the support 51.

Mounted on the support 60 is a jig fixture 67 which is illustrative of mountings that may be used on the rotary table for holding and positioning an irregular object in grinding relation with respect to the grinding element 26. The jig fixture 67, as shown, is of a form adapted to receive a rock bit segment B and to hold this segment in proper position for presentation of the raceway R thereof, into grinding relation with the element 26. The jig fixture 67 is shown accordingly as of inverted V-form in cross section to embrace the shank portion of the segment B and to confine the latter therein when pressed against

the inner side of the fixture by an angularly shaped dog 68 mounted on a fulcrum 69 upon the support 60, as shown in Fig. 8. One end of the dog 68, is engaged by a screw shank 70, shown as having threaded connection with the support 60 and provided with a hand crank for rotation thereof to tilt the dog 68 on its fulcrum 69 and cause one end of the dog to be turned in transverse relation with the under side of the segment B, holding the latter securely in the jig fixture 67.

The support 60 is shown as having upstanding sides between which the jig fixture 67 is fitted as will be evident from Figs. 8 and 9. This fixture is adapted to be secured in place on the support 60, for which purpose it is provided with a lug 71 engaged by a cross bar 72 that extends transversely over the jig fixture, as shown in Fig. 9. The opposite ends of the cross bar 72 are confined by tie bolts 73 connected therewith and extending downwardly to the turntable 48. The upper ends of these bolts 73 are provided with wing nuts 74 for tightening the cross bar 72 securely upon the lug 71 of the jig fixture.

A pair of dowel pins 75 protrude from the respective side faces of the jig fixture 67, perpendicularly thereto, in position to engage holes in the faces of the bit segment B which will provide a definite indexing of the bit body segment with respect to the jig fixture to insure proper alignment of the raceway R, with the abrasive element 26. By having the dowel pins 75 positioned on both faces of the jig fixture 67 and perpendicular thereto in accurate spaced relation, so as to interengage with holes provided in the rock bit segment, the latter may be brought quickly into accurate alignment without requiring adjustment, and segments presented and removed in succession without readjustment.

It is preferable that one of the dowel pins 75 be fixed to the corresponding face of the jig fixture 67, while the other dowel pin 75 may be removably mounted in the corresponding face of the jig fixture. Thus one of the dowel pins may be removed and inserted each time a bit segment is removed and another installed on the jig fixture. This serves to position the bit segment accurately in proper relation for operation thereon of the abrasive element.

After the bit segment B is in place and confined by the dowel pins 75, fitting into holes in the segment, the clamp 68 is moved into engagement with the under side of the bit segment B, by the manipulation of the adjusting member 70 and pressed firmly thereagainst to confine the shank of the bit segment within the V-shaped jig fixture 67. This insures a precise fit between the bit segment and the jig fixture and accurately positions the work with respect to the abrasive element.

As shown in Figs. 1 to 3, the lower end of the shaft 45 on which the turntable 48 is mounted, carries a pulley 76 keyed thereto. A belt 77 extends around the pulley 76 and around an idler pulley 78 mounted on an upright shaft 79 (Fig. 5). The shaft 79 also carries a pulley 80 of appreciably larger diameter than the pulley 78 and the latter is also materially reduced with respect to the pulley 76 to accomplish an appreciable speed reduction in the driving of the shaft 45. The pulley 80 is operatively connected by a belt 81 with a pulley 82 secured rigidly on the lower end of the jack shaft 30, as shown in Figs. 5 and 6, to be driven from the motor 38.

The shaft 79 is journaled in a sleeve 83 car-

ried by supporting arms 84 secured rigidly thereto. The arms 84 are pivotally mounted by means of a pin 85, extending through a sleeve 86 that is fixed to one side of the standard 2. A handle 87 is secured to the lower arm 84 for the purpose of swinging said arms to move the shaft 79 in an arc about the axis of the pin 85. The handle 87 may be secured in an adjusted position by means of a notched arcuate segment 88, adapted to be engaged by a spring-pressed latch 89.

As will be evident from Fig. 5, an arcuate adjustment of the position of the shaft 79 to the right will loosen the belt 77, while an adjustment toward the left will tighten the belt on the pulleys 76 and 78. Thus the belt tightener serves as a clutch for the rotation of the turntable 48 when shifted toward the right or left from the position shown. When the belt is in proper tightened relation, the parts may be secured rigidly by the latch 89.

In the operation of the machine, a rock bit segment B, in the form of the invention illustrated, is fitted and clamped to the jig fixture 67, as shown in Fig. 8, and is secured in place by the clamp 68, held by the screw shaft 70. In this form, it is desirable to adjust the raceway R, into proper peripheral relation to the grinding element 26. Such adjustments may be provided by shifting the respective supports 51 and 60, transversely and longitudinally relative to each other and with respect to the turntable 48, by relative rotation of the screw shafts 53 and 62.

It will be appreciated that by such adjustments of the supports transversely and longitudinally at right angles to each other, as well as to tilt either of the supports, and to raise and lower the grinding element 26, the axis of the bearing race R can be brought into the proper axial, aligned relation with respect to the axis of the turntable 48. This provides a universal movement for obtaining a correct adjustment of the work.

The bearing race R is shown as having a concave race cut therein. When the parts are properly adjusted, the turntable 48 is rotated in axial alignment with the bearing race R; the axis of the abrasive element 26 is offset with respect thereto, while the latter is rotated at a high rate of speed as compared with the lower rate of speed of rotation of the turntable. This will cause a groove to be cut in the bearing race.

The abrasive element 26 is adjusted eccentrically by the screw adjustment 41 to move the abrasive element toward and from the axis of the bearing race R. This element 41 adjusts the feed of the abrasive element during operation which adjustment is possible for different adjusted positions vertically of the abrasive element.

The formed abrasive element 26 may be used for internally grinding in cups or for externally grinding on raceways of cones, by adjustment of the screw 41, thereby causing a bodily shifting of the axis of the grinding element toward and from the center axis of the work. The hand wheel 12 provides for vertical adjustment of the abrasive element with respect to the work. When the abrasive element is in correct adjusted position, the threaded stem 14 forces the clamping segment 13 in binding engagement with the upper end portion of the sleeve 7.

While the adjustments have been described with respect to an operation on a bearing raceway, positioned substantially in axial alignment with the shaft 45, it is appreciated that the adjustments of the supports 51 and 60 are such that

the center of axial rotation of the cup or cone of a bearing raceway may be made eccentric with respect to the shaft 45, and with the spindle 21 positioned in axial alignment with the shaft 45, when an orbital movement is then accorded to the work, in such manner that the grinding element is in contact relation with a side of the work while the latter is rotated about the abrasive element which operates at a high rate of speed.

It will be appreciated that the unit is provided with various adjustments to accommodate either large or small races or for grinding races on irregularly shaped objects, such as may be used on a rock bit body segment, or a true race may be ground on any element which may be fitted in a jig, even though the element being acted on is irregular in shape or has special eccentricities which would not adapt it for use in a conventional ball race grinding machine. It is also possible to use this machine for grinding other objects than just races, wherever its practical utility may be advantageous.

A modified form of the invention is shown in Figs. 10 to 12, inclusive, and comprises a base 101 from which arises a standard 102. The standard 102 has a frame 103 projecting outwardly therefrom, and pivotally mounted thereon by a sleeve 104. The upper end of the standard 102 carries arms 105 and 106 which project radially outward from the standard, and have sleeves 107 and 108 secured to the outer ends of the arms 105 and 106, respectively, which sleeves secure a tubular shaft housing 109 in a substantially vertical position.

A motor 110 is mounted on the outer portion of the base 101 and has a belt 111 encircling a pulley 112 on the motor 110 and a pulley 113 on a shaft 114 that is journaled in bearings 115 and 116 substantially parallel to the standard 102. The upper end of the shaft 114 carries a pulley 117 which is in driving connection with a pulley 118 mounted on a shaft 119 by a belt 120.

The shaft 114 also carries a pulley 121 which drives a larger pulley 122 through belt 123 which encircles said pulleys. The pulley 122 is mounted on a shaft 124 which has a pulley 125 directly below said pulley 122. A belt 126 (Fig. 11) encircles the pulley 125 and a pulley 127, which pulley 127 is secured to a shaft (not shown) to which a rotary table 128 is secured. The shaft of the rotary table 128 is mounted in bearings 129 in the pivotal frame 103.

A holding and truing jig, generally designated at J, is mounted on top of rotary table 128 on a screw-threaded transverse shaft 130 (Fig. 12), extending substantially diametrically across the rotary table 128 and carries a table 131 upon which a screw-threaded shaft 132 is mounted that carries a table 133. A holding fixture 134 is mounted on top of the table 133 and has dowel pins to engage the work being handled. This holding fixture 134 is reversible so as to accommodate different sized articles that are to be ground.

After the table 131 has been adjusted transversely of the table 128, screw jacks 135, provided on either side of the table, are tightened for adjusting the table to the correct angularity with respect to the rotary table 128. Screw jacks 136 are provided for the adjustment of the table 133 to the correct angularity, after the adjustment of the screw-threaded shaft 132 has been accomplished. The screw jacks 135 and 136 hold these tables in adjusted position so as to main-

tain the article being ground in the correct adjusted position.

The fixture 134, as shown in Fig. 12, is of 120° angularity, which centers a rock bit segment B'. A bar 137 passes across the fixture 134 and projects outwardly therefrom and has screw-threaded nuts 138 on each end thereof for engagement with screw-threaded jacks 139, which enables an upward projection 137' on the bar to be pressed upward to hold the bit segment in place while the abrasive element 140, mounted on the shaft 119 is operated to perform the desired grinding action upon the bearing surfaces of the rock bit segment B'.

A screw-threaded shaft 141 (Fig. 10) threadably engages a nut 142 which is pivotally secured to the underside of the frame 103, and at the opposite end the threaded shaft 141 is secured against longitudinal movement to a bracket 143, which bracket is secured to the base 101. By the turning of a handle 144 on the screw-threaded shaft 141, the table 103 will be swung about the standard 102 as a center, and this will vary the axial alignment of rotary table 128 with respect to grinder shaft 119, thereby making possible minute adjustments for regulating the distance between the grinder 140 and the axial point of the work in the jig J.

In the operation of the device as shown in Figs. 10 to 12, inclusive, the rock bit segment B' or other work, is fitted into the fixture 134, and in the case of a rock bit segment B', dowel pins are fitted through holes in the jig and into holes provided in the rock bit segment so as to index properly the rock bit segment which is clamped in place by the bar 137. By manipulation of the threaded shafts 130 and 132 the tables 131 and 133 are shifted transversely with respect to each other so as to position properly the rock bit segment B', which bit segment is mounted in the fixture 134.

Upon starting the motor 110, the grinder shaft 119 is rotated at a high rate of speed. By engaging a handle 144 with a hook 145, the belt 126 is tightened so as to turn the rotary table 128 to rotate the bit segment B', Fig. 11, in an annular path around the axis of grinder shaft 119. As the grinding operation proceeds, the depth of the cut of the grinder 140 is regulated by turning the screw-threaded shaft 141 which will swing the frame 103 about the standard 102.

A vertical adjustment of the grinder shaft 119 is obtained by rotating a hand wheel 109' which has its inner bore threaded for engagement with the threaded portion of the tubular shaft housing 109. When the proper height of the grinder 140 is obtained, a clamp screw 108' is used bindingly to engage the outer bifurcated portions of the split sleeve 108.

It will be appreciated that this modified form of the invention is simple and compact in construction and that it may be adjusted readily in various ways to obtain the correct adjustments for performing various grinding operations.

While the invention has been illustrated and described in certain embodiments, it is recognized that variations and changes may be made therein, without departing from the invention except as specified in the claims.

I claim:

1. In a vertical spindle grinding machine of the character described, the combination of a rotatable spindle having an abrading element mounted thereon, a power driven turntable associated

with the abrading element and having a workholder mounted on said turntable, said workholder including a jig adapted to receive work therein, universal mounting means for mounting the jig on the table for shifting movement thereof to different angular positions relative thereto, and power means for driving said spindle and said turntable in coordinated relation.

2. In an abrading machine of the character described, the combination of an upright sleeve, an arm mounted on the sleeve and extending laterally therefrom, a second sleeve carried by the arm, an upright spindle journaled in the second sleeve, an abrading element carried by the lower end of the spindle, a turntable rotatably mounted below the abrading element and having means for supporting work thereon in operative relation with the abrading element, means mounting said arm for lateral swinging movement relative to the sleeve and for vertical adjustment relative thereto, a drive shaft associated with the first-mentioned sleeve, and means forming driving connections from said drive shaft to the spindle and turntable.

3. In an abrading machine of the character described, the combination of an upright sleeve, an arm mounted on the sleeve and extending laterally therefrom, a second sleeve carried by the arm, an upright spindle journaled in the second sleeve, an abrading element carried by the lower end of the spindle, a turntable rotatably mounted below the abrading element and having means for supporting work thereon in operative relation with the abrading element, means mounting said arm for lateral swinging movement relative to the sleeve and for vertical adjustment relative thereto, a drive shaft associated with the first-mentioned sleeve, means forming driving connections from said drive shaft to the spindle and turntable, and means for holding the arm in adjusted positions of swinging movement for different vertically adjusted positions of the spindle.

4. In an abrading machine of the character described, the combination of an upright sleeve, an arm mounted on the sleeve and extending laterally therefrom, a second sleeve carried by the arm, an upright spindle journaled in the second sleeve, an abrading element carried by the lower end of the spindle, a turntable rotatably mounted below the abrading element and having means for supporting work thereon in operative relation with the abrading element, means mounting said arm for lateral swinging movement relative to the sleeve and for vertical adjustment relative thereto, a drive shaft associated with the first-mentioned sleeve, means forming driving connections from said drive shaft to the spindle and turntable, and means for clamping one of the sleeves and the arm in relatively vertically adjusted positions for holding the spindle in properly adjusted positions.

5. In an abrading machine of the character described, the combination of an upright sleeve, an arm mounted on the sleeve and extending laterally therefrom, a second sleeve carried by the arm, an upright spindle journaled in the second sleeve, an abrading element carried by the lower end of the spindle, a workholder having means for supporting work thereon in operative relation with the abrading element, means mounting said arm for lateral swinging movement, means

for adjusting the spindle vertically, a clamp in position for secure clamping engagement with at least one of the sleeves for holding the spindle in fixed position, and means forming a driving connection with the spindle.

6. A workholder for a grinding machine comprising a table, a jig mounted on the table and adapted for receiving work therein, a transverse shaft mounting means for mounting the jig on the table, a second transverse shaft positioned below said first mentioned shaft at substantially a right angle thereto, and means of moving said jig along said shafts, means for holding said jig in a fixed position, and means for rotating said jig in coordinated relation to said grinding machine.

7. A workholder for a grinding machine comprising a table, a jig adapted to receive work, a shaft carried by the table and extending transversely thereof, a support mounted on the shaft and carrying a second table having a shaft mounted thereon at substantially a right angle to said first mentioned shaft, a support mounted on said second shaft and carrying the jig, means for adjusting the support axially of said shafts and a clamp member extending upward for cooperative clamping with work in said jig.

8. A workholder for a grinding machine comprising a jig fixture substantially inverted V-shaped in cross section adapted to receive work between the inner sides thereof, dowel pins carried by said inner sides and extending inwardly therefrom substantially at right angles to said sides in positions to engage the work, a pair of screw members positioned on each side of said V-shaped fixture and having an abridging screw threaded bar therebetween and operatively connected therewith for clamping work in said fixture.
